SAFETY DEVICE FOR HYDRAULIC MECHANISMS

Filed Nov. 22, 1929

UNITED STATES PATENT OFFICE

FRANK C. WILSON, OF ARCADE, NEW YORK

SAFETY DEVICE FOR HYDRAULIC MECHANISMS

Application filed November 22, 1929. Serial No. 409,175.

This invention relates to improvements in hydraulic mechanisms and in particular to a safety device for such a mechanism which is adapted to release the pressure behind the 5 working piston of the same at a point in its working stroke when a continued movement of the piston would likely result in the blowing out of the head of the cylinder.

It has been proposed heretofore, in order 10 to avoid blowing out the cylinder head of mechanisms of this kind to provide ports in the side walls of the cylinders at points where they would be in open communication with chambers behind the piston when the piston 15 had reached a point in its working stroke beyond which it would be dangerous to continue, the ports being normally on the opposite side of the piston from the working chamber of the cylinder and being placed 20 in direct communication with the working chamber when the piston passed them in its working stroke. This type of construction, however, has the objection that the sealing packing which is usually in the form of a 25 leather washer is often mutilated by portions of the same being cut off by or blown out through such ports, the result being that the sealed relation between the walls of the cylinder and the piston is broken and the fluid 30 actuating medium is permitted to escape past the piston without accomplishing any work.

The object of the present invention is to 35 avoid the mutilation of the sealing parts of the piston and proposes a construction in which the pressure behind the working piston is permitted to escape, when the piston has 40 reached the limit to which it can move with safety, by a port which extends through the body of the piston, the escaping medium being conducted by a suitable return pipe back to the fluid reservoir.

Further objects are to provide a safety device of the type described of simple construction, inexpensive to manufacture and which 45 can be readily applied to the desired mechanism.

The invention is illustrated in the accompanying drawing in which:

Figure 1 is a perspective of an arbor press 50 showing one application of the invention.

Figure 2 is a vertical section taken along line 2—2 of Figure 1.

Figure 3 is an enlarged sectional view taken along line 3—3 of Figure 2.

Figure 4 is a vertical section taken through 55 the fluid reservoir and the hand pump in communication therewith.

The invention is illustrated in connection 60 with an arbor press A. It is to be understood, however, that it may be utilized in any type 65 of mechanism which is provided with a working cylinder and a piston actuated member which forms the movable member of the mechanism.

In the embodiment illustrated, the arbor 70 press A includes in general a working cylinder C a movable member D and a work support S, all the parts named being mounted upon a suitable frame including upright legs 5 which may be of channel form.

The cylinder C is preferably suitably 75 mounted between cross members 6. The work support S is fixed upon similar cross members 6a which are adjustable to position the support S at the desired distance from the movable member D of the device.

The working cylinder C is suitably connected as by a feed pipe 7 to a fluid reservoir 8. In this form of apparatus it is the practice to utilize compressed air for light press- 80 ing operations and when this method of operation is resorted to, compressed air is admitted into the fluid reservoir 8 through a supply pipe 9 the fluid medium 10 in the reservoir being then forced out through the discharge opening 11 in the reservoir and through the opening 12 in the hand pump cylinder into the feed pipe 7 by which it is conducted to the working cylinder C. However, some pressing operations require greater 85 pressure than can be practically obtained by compressed air and in these cases it is preferred to employ a hand pump H having a plunger 12a and an operating handle 13, the handle 13 being preferably pivoted to 90 the head of the fluid reservoir as by the link 14. In any event, whether the fluid medium 10 be forced through the feed pipe 7 by compressed air or by the hand pump H, the piston P will be forced to the lower end of its 100

working stroke which is a short distance above the position shown in Figure 2. Upon the completion of the working stroke, the member D may be returned to its normal position by opening the valve 20a in the drain pipe 20b. This will permit the spring 15 which is positioned in an annular recess 16 in the lower head of the cylinder to force the piston to the upper position of its stroke, 10 the fluid medium behind the same being returned to the reservoir 8 through the feed pipe 7 and the drain pipe 20b, it being understood, of course, that by the operation of the piston P the movable member D of the device will be affected in a like manner.

In devices of this character it is the practice to provide the piston with a flexible sealing gasket of leather or the like which is adapted to form a tight seal between the 20 piston and the cylinder, the sealing member being, in the present instance, illustrated at 18 in Figure 2.

In order to avoid blowing out the lower cylinder head 17 by too great a downward movement of the piston P, I propose to release the pressure behind the piston at a time during its working stroke when a further movement would likely result in the blowing out of the lower cylinder head. 25 Heretofore it has been proposed, in order to avoid this danger, to provide ports in the wall which, upon the piston passing them would release the pressure in the cylinder. This method of avoiding the danger is objectionable as the flexible sealing member would be cut by passing over the ports or where comparatively high pressures are used there would be the possibility of a portion of the sealing member being blown out through 35 such ports, in either case a mutilated sealing member being the result.

In order to release the pressure in the manner desired while at the same time eliminating any possibility of mutilating the sealing member 18, I provide the piston P with a duct 19 which extends through the same and which is adapted upon being opened to permit the escape of the fluid medium from behind the piston, the escaping fluid being returned to the fluid reservoir by the return pipe 20 to enable its subsequent reuse.

The duct 19, mentioned heretofore, is normally closed by a ball valve 21 and is preferably formed longitudinally in the reduced end of the working member D about which the piston P is fitted and retained thereon as by nut 22. It is in open communication at its lower end with a transverse bore 22, the said 55 duct and bore providing a T-shaped recess within which is positioned the ball valve actuating means. The said means includes a stem 23 upon which the ball 21 is adapted to rest when the duct 19 is opened to release the 60 pressure behind the piston P. The stem 23

is carried by a cross pin 24 positioned in the transverse bore 22.

In the normal operation of the press, the working member D functions in the usual manner and the safety device is inoperative. 70 If for any reason, however, the piston P is permitted to move downward to a greater extent than is safe, the cross pin 24 will strike the shoulder 25 formed in the lower piston head 17 and move relatively upward in the 75 bore 22, this movement, of course, being imparted to the stem 23 and the ball 21 to raise the ball from its seat. Thereupon, the fluid medium behind the piston P will flow around the ball 21 through the duct 19 and the transverse bore 22 and into the annular recess 16 from whence it is returned to the reservoir 8 as described. The ball valve 21 may be confined in bore 19 in the reduced end of the working member D in any suitable manner 80 as by the apertured plug 26 which is preferably threaded in the upper end of said member.

Having described my invention, I claim:

A hydraulic mechanism including a cylinder having a piston adapted to operate the movable member of the mechanism and being in communication with a fluid reservoir, means for supplying fluid from said reservoir to said cylinder under pressure to operate 90 said piston and the movable member connected thereto, said member having a duct in communication with said reservoir and opening into said cylinder on the opposite side of said piston, said duct being normally closed by a ball valve, a stem movable longitudinally in said duct for operating said valve, a cross pin positioned in a bore in said movable member and co-operating with said stem, the lower head of said cylinder having an inwardly projecting annular shoulder which provides an annular drain chamber, said cross pin being adapted to engage said shoulder when said movable member approaches the safe limit of its range of movement to open said valve and permit the operating fluid to escape through said duct to said drain chamber, a pipe for returning the fluid from said chamber to said fluid reservoir and a spring in said chamber arranged 100 about said annular shoulder which is compressed during the working stroke of said piston and which is adapted to return the latter to its normal position after said working stroke.

In testimony whereof I affix my signature.
FRANK C. WILSON.
